MERCHANDISE DISPLAY STAND,
OR SIMILAR ARTICLE

Ronald H. Taub, Highland Park, Ill., assignor to Creative Displays, Incorporated, Chicago, Ill., a corporation of Illinois

Filed Jan. 13, 1966, Ser. No. 587

Term of patent 14 years

(Cl. D80—9)

F1 G - 7

F1 G - 8

F1 G - 9

FIGURE 1 is a perspective view of one embodiment of a merchandise display stand, or similar article, showing my new design;

FIGURE 7 is a perspective view of another embodiment of a merchandise display stand, or similar article, showing my new design;

I claim:

The ornamental design for a merchandise display stand, or similar article, as shown and described.
